UNITED STATES PATENT OFFICE.

FREDERICK T. SNYDER, OF OAK PARK, ILLINOIS, ASSIGNOR TO INDUSTRIAL ELECTRIC FURNACE COMPANY, OF CHICAGO, ILLINOIS, A CORPORATION OF INDIANA.

ELECTRIC FURNACE AND METHOD OF OPERATING SAME.

1,379,942.

Specification of Letters Patent. Patented May 31, 1921.

Application filed October 23, 1913. Serial No. 796,746.

To all whom it may concern:

Be it known that I, FREDERICK T. SNYDER, citizen of the United States, residing at Oak Park, in the county of Cook and State of Illinois, have invented a certain new and useful Improvement in Electric Furnaces and Methods of Operating Same, of which the following is a full, clear, concise, and exact description.

10 My invention relates to improvements in electric furnaces. The objects of my invention are: to provide an improved method of automatically regulating the electric power supply of an electric furnace so as to maintain a uniform temperature in the furnace; to prolong the life of the furnace parts; and to provide a novel construction by means of which the above mentioned method of regulation may be carried out more advantageously than with existing types of furnaces.

20

In the accompanying drawing I have shown in Figure 1, a diagram by reference to which the features and underlying principles of the invention will be more readily understood. Fig. 2 is a sectional elevation of an improved form of furnace, in connection with which my improved method may be advantageously carried out. Figs. 3, 4, 5 and 6 are diagrammatic representations of modified forms of the invention.

Before describing a furnace structure embodying my invention, I shall set forth the underlying principles thereof by reference 35 to the diagram, Fig. 1. As introductory to such description, I shall explain the meaning of certain terms hereinafter used.

A constant potential supply of alternating current, as said expression is used herein, is one in which the average of the voltage during each alternation remains the same during successive alternations.

The equilibrium temperature of the resistor, as used herein, is the temperature at 45 which the radiation of heat energy from the resistor exactly balances the electric input of energy absorbed by the resistor.

A conductor or resistor with a negative temperature coefficient is one in which the 50 resistance decreases with increase of temperature, as, for example, in the case of a carbon rod. It is to be noted that an electric arc is a resistor with a negative temperature coefficient, since the resistance of the arc

diminishes with increased average temperature.

A conductor with a positive temperature coefficient is a conductor in which the resistance increases with increase of temperature, as, for example, a metal wire. If an electric current be passed through a metal wire, the wire will heat up from the resistance to the passage of the current. As the wire becomes hotter than its surroundings it will radiate heat. Roughly this radiation, according to the well recognized law of Stefan's, will vary proportionally to the difference of the 4th power of the absolute temperatures of the wire and its surroundings. As the wire gets hotter, its resistance increases. With a constant potential source of electric current this increase of resistance diminishes the energy input. As the energy input decreases with increased temperature, and as the radiation increases, a temperature will be reached at which the energy input and the radiation output will balance and the system will operate in stable equilibrium at that definite temperature. Under usual commercial conditions the length and diameter of the wire can be so chosen with reference to the potential of the current supply that the temperature at which the electric input and radiation output balance will be below the melting point of the wire. Stable electric heaters are constructed on this basis.

If an electric current be passed through a carbon rod, a conductor having a negative temperature coefficient, the rod will heat up from the resistance to the passage of the current. As the rod becomes hotter, its radiation of heat increases. At the same time the resistance of the rod will decrease. With a constant potential source of electricity, under ordinary conditions, this will cause more current to flow through the rod, producing more energy to be radiated. If the surroundings of the rod be kept fairly cool, the amount radiated will increase rapidly with the temperature, owing to Stefan's 4th power law. The resistance decreases with increase of temperature at a much slower rate, so that eventually the radiation will catch up with the input and the temperature of the rod will not rise further. Owing to the negative temperature coefficient of the carbon, this equilibrium temperature is

much higher than with a metal wire having a positive temperature coefficient. With a carbon rod exposed to surroundings kept fairly cool, the diameter and length of the rod can be chosen to reach this equilibrium temperature, using ordinary low pressure constant potential voltages, as, for example, in the case with an incandescent lamp.

Referring now to Fig. 1, the axis of the abscissæ is a measure of temperature in degrees centigrade and also of current in amperes, while the axis of the ordinates is a measure of electric energy in kilowatts and also of potential in volts. The curve A shows the energy radiated from a selected resistor with no heat insulation around it.

In case the selected resistor is a metallic wire, the line or curve C shows the energy developed therein when a constant electric potential is applied to the terminals of the wire. The slope of the line C indicates that the energy input diminishes with increase of the temperature of the resistor. The intersection of the curves A and C indicated by the point D gives the equilibrium temperature of this resistor, in the case assumed, of a resistor having a positive temperature coefficient.

In the diagram, the curve or line F shows the energy developed by a resistor having a negative temperature coefficient and with constant potential applied to its terminals. It will be seen from the slope of the line that the energy increases with increase of temperature. The point of intersection G of this line with the radiation curve A gives the equilibrium temperature. It will be seen that the equilibrium temperature in the case of a resistor having a negative temperature coefficient is greater than in the previous case of a wire resistor having a positive temperature coefficient, for the same initial energy input.

With electric furnace work, the purpose is to heat the material to be treated, usually to a high temperature. If a carbon rod be used as a resistor for this purpose, it no longer can radiate to cool surroundings, since radiation, in properly built furnaces, is prevented as far as practical and the heat is held in the furnace until the temperature is reached which is required for the material under treatment. This forces the carbon rod (with a constant potential current supply) to go to much higher temperatures to reach the equilibrium temperature. As the rod gets hotter, the furnace also gets hotter (conduction being largely prevented) and this action further raises the equilibrium temperature until it goes above the destruction temperature of the furnace material. That is, with the usual commercial conditions, a furnace heated by a resistance having a negative temperature coefficient, with constant potential current supply and good

heat insulation does not regulate for any permissible constant temperature, but gets hotter and hotter until the materials of the furnace break down.

In the diagram the curve B shows the energy radiated by a resistor inside of an electric furnace provided with good heat insulation. As the inside of the furnace also is hot, a resistor of given dimensions must go to a much higher temperature to radiate any given amount of energy inside such a furnace than where it can radiate to cool surroundings. The curve B intersects the line C at a point E representing a temperature very much higher than the point D. 80

If a carbon resistor, inside a furnace having good heat insulation, be placed in series with a ballast resistance arranged to operate at substantially constant temperature outside the furnace and the series supplied with electricity at constant potential, the available voltage will divide between the ballast and the carbon resistor in proportion to their resistance. The hot resistance of the carbon resistor may be one-third the cold resistance. If the cold resistance of the carbon resistor and the ballast be equal, they will then divide the voltage equally between them and half the energy due to the flow of the current will be developed by the carbon resistor in the furnace and half will be wasted by the ballast resistance outside the furnace. When the carbon resistor and the furnace are hot, if the resistance of the carbon resistor be one-third that of the constant ballast resistance, the sum of the two resistances in series, when the carbon resistor is hot, will then be two-thirds of what the sum was when the carbon resistor was cold. With constant potential applied to the series, the flow of current will be one and one-half times the flow that occurred when the resistor was cold. When cold the carbon resistor absorbs one-half the total voltage. 105 When hot it absorbs one-fourth of the total voltage. The other three-fourths is thus wasted in the ballast. The current flow with the carbon resistor hot is one and one-half times the flow with carbon resistor cold. Therefore the energy developed by the hot resistor in the furnace (volts multiplied by current) is $\frac{1}{4} \times 1\frac{1}{2} = \frac{3}{8}$ of the energy developed by the resistor when cold. That is, the energy supplied to the carbon resistor decreases with increase of temperature while the radiation from the carbon resistor increases as before with increase of temperature. This results in equilibrium being reached at a much lower temperature than where no ballast resistance is in series. 115

In the diagram, the curve L shows a resistor having a negative temperature coefficient in series with a ballast resistance. This line slopes more rapidly than the line 130

C, which latter shows the energy developed in a wire resistor. The intersection of the line L with the curve B is indicated by the point M and represents a temperature which, while it is much higher than the temperature indicated by D, is nevertheless not so high as the equilibrium temperature E, the latter representing a wire resistor.

10 By making the ballast resistance large enough in proportion to the resistor resistance, a carbon resistor, inside a furnace with good heat insulating walls, can be made to come to equilibrium temperature at any desired commercial temperature. However, the energy developed in the ballast resistance is wasted. In the example given, such wasted energy is three-fourths of the total energy consumed. Under the usual commercial conditions of constant potential distribution voltage and practical furnace dimensions, the amount of the total energy lost in this way makes this matter of a ballast resistance very uneconomical for temperature regulation. Hence I shall now describe the principles underlying a more commercial adaptation of my invention.

If alternating current is used from a source of constant potential, a reactor can be used for ballast instead of a resistance. This has the advantage that the voltage drop through the reactor does not represent an energy loss. This makes it practical, under the usual commercial conditions of constant potential electricity supply and practical furnace dimensions, to design a resistor that will reach equilibrium temperature corresponding to the usual industrial requirements.

40 With the resistor ballast, the voltage available for the resistor diminishes directly in proportion to the current flow. A ballast reactor has the advantage over the ballast resistance in that the voltage absorbed by the reactor is approximately in quadrature (90° phase) with the voltage left available for the resistor. This latter voltage, therefore, diminishes more and more rapidly with increase of current flow, so that equilibrium temperature is more promptly reached.

If the proportion of the voltage absorbed by the reactor be made relatively large, the drop in the rate of input of energy with increase of temperature becomes so rapid that the equilibrium temperatures for an exposed resistance and for one inclosed in insulating furnace walls do not differ materially.

In Fig. 1 the curve H shows the energy developed by a resistor having a negative temperature coefficient, in series with a reactor on a constant potential supply. This curve intersects the radiation curve A at the point J and it also intersects the radiation curve B at the point K. It will be noted 55 that the latter intersection represents a tem-

perature only slightly higher than the former temperature and shows that, under these conditions, the equilibrium temperature is only slightly higher in an electric furnace where heat insulation is employed, than with an exposed resistor without heat insulation.

Heretofore electric furnaces have been designed to have as little reactance in their circuits as possible, great efforts being made, (as by interlacing conductors and arranging iron parts to carry small magnetic fields), to reduce the reactance to a minimum. On the contrary, for the purposes of my invention, I make the reactance as large as is commercially practical, ordinarily using a reactance that absorbs not less than 29% of the constant potential voltage at the normal full load current of the furnace.

Referring again to Fig. 1, the curve N illustrates the voltage available at the resistor with different current flows, where the resistor is in series on a constant potential supply with a reactor absorbing 29% of the constant potential voltage, when the furnace is absorbing its normal full load current. The curve H is proportional to the corresponding energy, each point being the product of the current flowing in the resistor multiplied by the voltage at the terminals of the resistor.

With any furnace, a given current flow with a given voltage corresponds to a certain resistance which may be stated in ohms. Part of these ohms of resistance will be in the resistor and part in the reactor. The former may be designated as resistance ohms and the latter as reactance ohms. These two ohmic quantities are in quadrature with each other. Under the conditions in which I operate my furnace on the drooping side of the energy curve, the reactance ohms are larger in number than the resistance ohms.

In Fig. 2 I have illustrated a simple furnace construction with which the foregoing described method may be advantageously carried out. It is to be understood that said method may also be carried out with various types of electric furnaces now in use. The main walls 1 of the furnace are constructed of brick or other heat insulating material. The shape and construction of the furnace may vary, within wide limits, in accordance with the particular requirements at hand, the form illustrated being typical of a furnace wherein the molten bath of metal constitutes one of the electrodes. The side walls of the furnace are laminated, being made up of a plurality of thin plates or rings 2, 3, of metal having magnetic permeability, as for example the rings or plates may be made of steel. The thickness and the number of the rings or plates employed may be varied within a considerable range. The laminated rings in this construction

constitute the magnetic core of the reactor, and are so designed as to insure the operation of the furnace on the drooping side of the energy curve H. An electrode 4 projects through the roof of the furnace and a suitable conductor 5 passes through the base of said furnace, being in electrical connection with the molten bath 6 therein. The furnace is supplied with current from an alternating current source 7 through the conductors 8. Under certain conditions an additional ballast reactor 9 is connected in the external circuit. Under other conditions such additional reactor is not necessary.

Where my invention is carried out in connection with furnaces other than with the one described, wherein the reactor constitutes part of the furnace construction, all of the necessary reactance may be inserted in the external circuit. Such an arrangement is shown in Fig. 3, the reactor 9 in the external circuit constituting substantially all of the reactance of the circuit. In this figure the same reference characters have been used as in Fig. 2 where corresponding parts are illustrated.

It will be noted from the energy curve H that there are two points thereon corresponding to each value of the kilowatt input, one having a high current and a relatively low voltage and the other having a low current and a relatively high voltage. This permits a heat in the furnace to be started with a long arc at high voltage and small current and finished with a short arc at low voltage and high current. As a result of the short arc, a shadow is thrown on the roof of the furnace by the electrode, that is, the electrode acts as a shield for the roof, thereby protecting the latter from the heat of the arc. In general, by regulating in this manner, the refractory lining is not injured by high temperatures, and accordingly the useful life of the furnace is prolonged.

In making steel in an electric furnace where it is essential that the composition of the metal to be produced shall be within close analytical limits for the different elements, it is important that the furnace temperature should be maintained constant while making the analysis. As there is no consumption of heat, only the heat necessary for radiation has to be supplied at this time. This can be accomplished effectively by shortening the arc, which materially reduces the energy input into the furnace. Shortening the arc reduces the resistance of the arc and thereby increases the current flow. This increased current flow through the apparatus described, more than proportionately reduces the voltage applied to the furnace terminals so that the shortening of the arc results in a reduction of the

energy supplied to the furnace. The various adjustments of the electrode may be made manually by the attendant who adjusts the electrode in accordance with conditions as indicated by a watt meter.

Heating a cold charge with a long arc at high voltage and high energy input, insures rapid melting without injury to the walls and roof as the heat energy is absorbed readily by the comparatively cold charge as it melts. After it becomes molten and during the refining operation a short arc at low voltage and reduced energy input is employed to economize power and avoid damage to the refractory lining during this period when much less heat energy will maintain the molten bath at the required temperature.

The variable voltage applied to the resistor, heretofore described as obtained by means of a reactance built into the furnace, or put in series in the furnace circuit, may also be obtained from a transformer with a high reactance, taking current at constant potential and delivering energy at a voltage which drops so rapidly above full load furnace current that a further increase of current causes a reduction of the energy absorbed by the furnace. A circuit containing such a transformer is indicated diagrammatically in Fig. 4. The transformer comprises primary windings 10 and secondary windings 11, the remaining parts being indicated by reference characters corresponding to those previously used.

Where the constant potential electric supply is direct current, a reactor cannot be used. I obtain a similar result, however, by supplying the furnace from a compound wound direct current generator, in which the series winding is so proportioned and connected that the voltage given by the generator drops so rapidly with increase of current flow that when the furnace is operated with full load current, any increase in this current will reduce the voltage enough to reduce the energy input to the furnace below full load. An electric furnace supplied from such a compound wound generator is illustrated in Fig. 5, the generator being shown by the conventional diagram 12.

In Fig. 6, I have shown an electric furnace supplied from a circuit which comprises a reactor 13 of any suitable form in series with the resistor 4 and also in series with the secondary windings 14, 15, 16, of a plurality of transformers, said secondary windings being also connected in series with each other. The primary windings 17 of the transformer are connected to a suitable source of three-phase alternating current 18.

The particular furnace construction described above not only permits of the use of

metal rings as the magnetic core of the reactor itself, but it also provides for a very efficient heat insulation, as I have found that the temperature drop between the layers of metal, though held in contact with each other, is high. Since the side walls are laminated, being made up of thin metal plates 2, 3, in close contact with each other, there will be a joint between the adjacent bands and, in addition, another joint between the innermost band and the brick lining. Although metal itself is a good heat conductor, there is a large drop of heat potential across each joint, the total drop across the several joints being very high as compared to the drop across the refractory lining. Of course, the heat potential drop across the metallic band may be increased by increasing the number of said bands, and may therefore be made a greater proportion of the total drop between the inside of the furnace and the outer air. So far as the use of the metal bands for the purpose of heat insulation is concerned, they might well be made of any suitable material, but they are preferably made of steel in order that they may also serve as the magnetic core of a reactor.

The metal bands not only perform the function of acting as reactors and as heat insulators but they also serve to mechanically reinforce the furnace. Their effectiveness as heat insulators is unusually great, and, in cases where the temperature in the interior of the furnace is as high as 1500° C., for example, the exterior shell is not so warm but what the hand may be held against it without inconvenience. The invention may be embodied in forms other than those described herein.

What I claim is:—

1. The method of regulating the temperature of an electric furnace having refractory heat insulating walls and provided with a resistor having a negative temperature coefficient, which consists in subjecting the circuit of the electric supply to means which decreases the energy developed in the furnace with an increase in the current flow through said resistor.

2. The method of regulating the temperature of an electric furnace having refractory heat insulating walls and provided with a resistor having a negative temperature coefficient, which consists in subjecting the operating current to reactance sufficient in amount to decrease the energy developed in the furnace as the current flow increases.

3. The method of regulating the temperature of an electric furnace which consists in heating the furnace with a resistor having a negative temperature coefficient and supplying said resistor with electric current having a potential which drops with increased current flow proportionally faster

than the resistance of said resistor diminishes with increase of temperature due to the current flow.

4. The combination with an electric furnace having refractory heat insulating walls and a resistor with a negative temperature coefficient, of a source of electric supply, and means for varying, inversely with the current flow, the voltage applied to said resistor from said source of electric supply. 75

5. In combination, an electric furnace having refractory heat insulating walls, a reactor and a source of alternating current supply, said reactor being so designed as to absorb approximately 29% of the constant potential voltage at normal full load furnace current. 80

6. An electric furnace having refractory heat insulating walls and having a reactance sufficient to make the full load power factor less than 75% at normal full load furnace current. 85

7. The combination with an electric furnace having refractory heat insulating walls, of a source of constant potential electric current, a resistor within the walls having a negative temperature coefficient, and a reactor outside the walls connected in series with the resistor to the source of current, the reactor being so proportioned that the energy developed by the resistor will diminish with an increased flow of current. 95

8. The combination with an electric furnace having heat insulating walls, of a resistor having a negative temperature coefficient in series with a reactor, the resistance ohms being smaller than the reactance ohms. 100

9. The combination with an electric furnace having heat insulating walls, a reactor embodied in the furnace construction, and an alternating current supply for the furnace. 105

10. The combination with an electric furnace, of an alternating current supply and a reactance partly within and partly without the furnace in series therewith. 110

11. An electric furnace having a resistor with a negative temperature coefficient and having concentric metal plates in contact, constituting a heat insulating wall, said plates serving also as the core of a reactor. 115

12. An electric furnace having a refractory receptacle for the molten material, said receptacle being surrounded by a plurality of thicknesses of metal plates in contact with each other, forming a heat insulating casing therefor. 120

13. In an electric furnace, means for holding the bath of molten metal and a reinforcing heat insulating shell therefor, comprising more than two metal cylinders in contact with each other. 125

14. An electric furnace having a thick refractory inner wall, an outer reinforcing casing therefor consisting of metallic 130

6
laminae in contact with each other and at a substantial angle to the lines along which the heat tends to radiate.

15. The method of operating an electric furnace having refractory heat insulating walls and an arc resistor with a negative temperature coefficient, which consists in starting a heat with a long arc and finishing the heat with a shorter arc.

10 16. The method of operating electric arc furnaces, which consists in starting the furnace with a long arc at high voltage and small current, and finishing the heat with a short arc at low voltage and high current.

15 17. The method of operating an electric furnace having refractory heat insulating walls, an arc resistor with a negative temperature coefficient, and supplied from a variable voltage source of power, which consists in starting a heat with a long arc and finishing the heat with a shorter arc.

20 18. The method of operating electric arc furnaces from a variable voltage source of power, which consists in starting the furnace with a long arc at high voltage and small current, and finishing the heat with a short arc at low voltage and high current.

25 19. The process of refining metal in an electric arc furnace which consists in carrying out the melting process with a relatively high voltage and a corresponding long arc and then shortening the arc while lowering the potential for the refining process.

30 20. The method of melting and refining

steel and other metals which consists in forming an electric arc between a furnace electrode and the metal to melt the latter and subsequently forming a shorter arc with lower voltage between said electrode and the slag over the molten metal in refining.

40

21. The method of operating an electric arc furnace supplied with alternating current which consists in increasing the length of the arc gap within the furnace while maintaining the current value during a part of an operating period when a high energy input is desired and subsequently reducing the length of the arc gap to operate with lower energy input.

22. The method of operating with an alternating current an electric arc furnace charged with iron or steel, the electrodes of which tend to assume during part of the melting period such position with respect to the charge that a magnetic flux is induced into the charge, which consists in increasing the arc length and the operating voltage while substantial magnetization of the charge takes place, and when the charge has become melted reducing the arc length and the operating voltage.

In witness whereof I hereunto subscribe my name this eighteenth day of October, A. D. 1913.
